UNITED STATES PATENT OFFICE

95,276

DESIGN FOR A TUBE OR SIMILAR CONTAINER

Frank McIntosh, New York, N. Y., assignor to
Lentheric Incorporated, New York, N. Y., a
corporation of New York

Application January 23, 1935, Serial No. 55,001

Term of patent 7 years

To all whom it may concern:

Be it known that I, Frank McIntosh, a citizen of the United States, residing in the Borough of Manhattan, in the city and county of New York, and State of New York, have invented a new, original, and ornamental Design for a Tube or Similar Container, of which the following is a specification, reference being had to the accompanying drawing, forming part thereof.

In the drawing, the figure is a perspective view of a container showing my new design. The

oblique hatching on the transverse stripes represents shading; the black lines on the white background represent high lights; and the fine white lines on the walls of the cap represent ridges and the remaining white areas on the black background represent high lights.

I claim:

The ornamental design for a tube or similar container substantially as shown and described.

In witness whereof I affix my signature.

FRANK MCINTOSH.
